(57) **CLAIM**

The ornamental design for a camera, as shown and described.

DESCRIPTION

FIG. 1 is a front, top, and right side perspective view of a camera.

FIG. 2 is a front elevational view of the camera.

FIG. 3 is a rear elevational view of the camera.

FIG. 4 is a right side elevational view of the camera.

FIG. 5 is a left side elevational view of the camera.

FIG. 6 is a top plan view of the camera.

FIG. 7 is a bottom plan view of the camera; and,

FIG. 8 is a rear, top, and left side perspective view of the camera.

The broken lines depict portions of a camera in which the design is embodied and form no part of the claimed design.
